UNITED STATES PATENT OFFICE.

HERMAN J. RUDULPH, OF NEW YORK, N. Y., ASSIGNOR TO MERGENTHALER LINOTYPE COMPANY, A CORPORATION OF NEW YORK.

MOLD FOR TYPOGRAPHICAL MACHINES.

1,157,808.

Specification of Letters Patent. Patented Oct. 26, 1915.

Application filed October 26, 1912. Serial No. 727,852.

To all whom it may concern:

Be it known that I, HERMAN J. RUDULPH, a citizen of the United States, and a resident of New York, county of New York, and 5 State of New York, have invented a new and useful Improvement in Molds for Typographical Machines, of which the following is a specification.

My invention has reference to typographical casting machines and aims at the provision of a mold of improved construction to produce type bars of special form for use in printing plain or ornamental designs around advertisements, book pages, etc. It 10 is now common practice to employ for this purpose slugs or linotypes having a longitudinal border thereon, these slugs being arranged at right angles to one another and with their ends joined to form the corner of 15 the border. In practice much difficulty is encountered in connecting and confining the ends accurately and in such manner as to produce a close joint and an unbroken design. To obviate this objection, I propose to 20 construct the mold of such form that it will produce a printing bar or slug with its opposite ends offset to the other portion, as for instance turned up at right angles or in 25 some other manner, and with the rule or border thereon extending lengthwise and also turned at the corner, so that a vertical 30 slug bearing the same rule or border may be joined to the other conveniently. This arrangement avoids the necessity for using 35 separate corner pieces and also the break or disconnection which frequently occurs when it is attempted to joint mitered slugs.

In the accompanying drawing I have shown my invention merely in preferred 40 form and by way of example, and I desire it to be understood that I do not limit myself to any specific form or embodiment except in so far as such limitations are specified in the claims. It is of course manifest that the 45 printing design of the cast slug may be varied in any desired manner.

Referring to the drawing: Figure 1 is a view of a slug produced by my improved mold, and showing its mode of employment 50 in connection with coöperating slugs; Fig. 2 is a detached view of a mold constructed in accordance with my invention; Fig. 3 is a transverse section taken substantially on the line 3—3 of Fig. 2; Fig. 4 is a similar

section taken on the line 4—4 of Fig. 2; and 55 Fig. 5 shows a special form of liner included in the mold construction.

The mold comprises as usual the cap portion C and the body portion D. Located between these parts is a liner E formed with 60 a longitudinal slot or depression e, constituting the mold cavity proper, and at the opposite ends of the depression e, the liner is formed with transverse grooves e¹ communicating with the slot e. It will be noted 65 that the bottom wall of the depression e and the opposing face of the overlying cap portion C are both plain or smooth throughout so that the slug cast in the intervening mold space will be solid or unrecessed in its 70 side face.

Fig. 1 shows a slug A produced by my improved mold. The main or body portion of the slug is cast in the slot e and its offset ends A¹ in the transverse grooves e¹, it being noted that the grooves e¹ project laterally from the slot e so that the offset portions A¹ project beyond the effective side face of the slug. The slug is formed with a printing projection a which extends not 80 only along the body of the slug but is also turned at its ends to extend to the extremities of the offset portions A¹, in such manner that it meets and joins with similar printing projections b on the vertical coöperating slugs B. 85

It will be noted that the recesses wherein the slug and its offset ends are cast are formed wholly in the liner E. This is advantageous since, by removing the liner and 90 substituting others of the usual kind, the mold may be employed for producing slugs of the ordinary construction.

Having thus described my invention, its construction and mode of operation, what I 95 claim and desire to secure by Letters Patent of the United States, is as follows:

1. A linotype mold having a longitudinally extending slot wherein the slug is cast, the side walls of said slot being plain or straight 100 throughout so as to produce a solid or unrecessed slug, and one of said walls being formed at one end of the mold slot with a transverse groove projecting laterally therefrom and communicating therewith and into 105 which the casting metal flows to produce on the slug an offset portion which projects beyond its effective side face and which is

formed with a printing projection extending longitudinally along the body of the slug and bent at the end.

2. A linotype mold having a longitudinally extending slot wherein the slug is cast, the side walls of said slot being plain or straight throughout so as to produce a solid or unrecessed slug, and one of said walls being formed at the opposite ends of the mold slot with transverse grooves projecting laterally therefrom and communicating therewith and into which the casting metal flows to produce on the slug at its opposite ends offset portions projecting beyond its effective side face and which is formed with a printing projection extending longitudinally along the body of the slug and bent at the end.
3. A mold element formed with a longitudinally extending slot or depression passing transversely through the element from one edge to the other and with a transverse groove located at one end of the slot and communicating therewith.
4. A mold element formed with a longitudinally extending slot or depression passing transversely through the element from one

edge to the other and with a transverse groove located at each end of the slot and communicating therewith.

5. A linotype mold comprising, in combination, top and bottom parts, and an intermediate mold element formed in its side face with a longitudinally extending depression passing transversely through the element from one edge to the other constituting the mold slot proper, and further formed with a transverse groove located at one end of the slot and communicating therewith.

6. A mold having a longitudinally extending slot, the said slot being formed wholly in one of the side walls of the mold, and the said wall being formed at one end of the slot with a transverse groove communicating therewith whereby a printing surface having elongated and bent-end portions may be cast.

In testimony whereof I hereunto set my hand this twenty third day of October, 1912, in the presence of two attesting witnesses.

HERMAN J. RUDULPH.
